UNITED STATES PATENT OFFICE.

JAMES A. IRVING, OF COLUMBUS, OHIO.

DESIGN FOR A SIGN-LETTER.

SPECIFICATION forming part of Design No. 26,078, dated September 22, 1896.

Application filed May 2, 1896. Serial No. 590,035. Term of patent 14 years.

To all whom it may concern:

Be it known that I, JAMES A. IRVING, a citizen of the United States, residing at Columbus, in the county of Franklin and State of Ohio, have invented and produced a new and original Design for Sign Letters or Characters; and I do hereby declare the following to be a full, clear, and exact description of the same, reference being had to the accompanying drawings forming a part thereof.

In the drawings referred to, Figure 1 illustrates the sign-letter embodying my design, and Fig. 2 shows an edge view thereof.

As shown in the views, the outer side or face of the letter is made with a series or succession of parallel ridges 2, the upper surfaces of which are flat, with inwardly-rounded or concave grooves 1 between them, while the under side of the letter is flat or plain.

The ridges and grooves are arranged diagonally across the letter.

The leading feature of my design consists of the letter having its outer surface comprising a series or succession of diagonally-arranged ridges having flat faces with inwardly-rounded concave grooves between them, and provided with a plain under side or base, as shown.

I claim and desire to secure by Letters Patent—

The design for a sign-letter, substantially as herein shown and described.

In testimony whereof I affix my signature in presence of two witnesses.

JAMES A. IRVING.

Witnesses:

B. C. BLACHLEY,
GEO. M. FINCKEL.
